Primary Examiner — Carla Wright(74) *Attorney, Agent, or Firm* — Altis Law Group, Inc.(57) **CLAIM**

The ornamental design for a cover of an electronic device with surface pattern, as shown and described.

DESCRIPTION

FIG. 1 is a perspective view of a cover of an electronic device with surface pattern showing our new design; FIG. 2 is a front elevational view thereof; and, FIG. 3 is a side elevational view thereof.

In the drawings, the broken lines indicate portions of the cover of an electronic device with surface pattern that form no part of the claimed design.
